The ornamental design for an automobile front grille, as shown and described.

DESCRIPTION

FIG. 1 is a front and right side perspective view of the automobile front grille showing my new design;

FIG. 2 is a rear and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a front and right side perspective view thereof, wherein the automobile front grille is shown installed on environmental automobile.

In FIG. 8, the de-emphasized, halftone, or ghosted showing of the automobile is provided for the purpose of illustrating environmental structure and forms no part of the claimed design. Also the broken lines in FIG. 8 illustrate boundaries of the claim and do not form part of the claimed design.
